United States Patent Office

Des. 187,277
Patented Feb. 23, 1960

187,277

WINDOW MOUNTED SHELF

Carl P. Rumbaugh, Southampton, Pa., assignor of one-half to John Andrew Meyer, Jenkintown, Pa.

Application May 9, 1958, Serial No. 50,821

Term of patent 14 years

(Cl. D33—3)

FIG. 1

FIG. 2

Fig. 1 is a perspective view of a window mounted shelf embodying my new design; and

Fig. 2 is a side elevational view thereof.

I claim:

The ornamental design for a window mounted shelf, substantially as shown.
